MOLD JACKET

David A. Cellings, Cleveland, Ohio, assignor to
Hazel K. Hines

Application August 24, 1938, Serial No. 226,503

5 Claims. (Cl. 22—112)

This invention relates to a mold jacket and method of making same and is particularly directed to a jacket having corners entirely open but resiliently connected. The present jacket departs from the two previously known practices of either having a jacket entirely rigid or having the sides mutually entirely loose within certain limits. Here the jacket is held to a firm and accurate relation of the sides, just as in an absolutely rigid jacket, and this relation is maintained as long as a definite degree of stress is not exceeded. When this stress is exceeded, the sides move relatively to one another. In other words, although the jacket is initially made to rigid accuracy, the corner connections are springs sufficiently stiff to maintain the basic size of the jacket, but allow the sides to spread beyond such basic dimensions, and to conform themselves, within limits allowed by the resilient connections, to being placed higher up or further down on a sloping sided sand mold.

To the accomplishment of the foregoing and related ends, said invention, then, consists of the means hereinafter fully described and particularly pointed out in the claims.

The annexed drawing and the following description set forth in detail certain structure embodying the invention, such disclosed means constituting, however, but one of various structural forms in which the principle of the invention may be used.

In said annexed drawing:

Fig. 1 is a perspective view of my improved jacket;

Fig. 2 is a side elevation;

Fig. 3 is a corner detail looking downward and omitting the taper for simplicity;

Fig. 4 is an elevation of a fastening detail, showing the face which in assembly goes against the jacket side;

Fig. 5 is a plan view of the drag half only of a molding jig for use in the manufacture of the corner fastenings; with the fastenings sectioned on the plane 5—5 of Fig. 7;

Fig. 6 is a vertical section on the plane 6—6 of Fig. 5; and

Fig. 7 is a vertical section on the plane 7—7 of Fig. 6.

The description and illustrations of my improved jacket are on a basis of the conventional 4-sided mold jacket, but it will be understood that the principles are applicable with jackets with a different number of sides.

As shown in Fig. 1, the jacket comprises separate end slabs 1, 1 and side slabs 2, 2, all gen-

erally designated by the word "sides," spaced at the ends so as to give the jacket open corners, and connected at such corners by stiff strap springs 4 of approximately L-shape with reentrant ends, such ends being embedded in fastening pads or escutcheon plates 5 which may conveniently be of approximately triangular outline and to which the slabs 1 and 2 are bolted or riveted as at 12. These pads are preferably cast on the ends of the spring, but it will be apparent that other mechanical arrangements may be used for the same purpose.

Where so cast, the casting may be accomplished by a permanent mold or casting jig 10, Fig. 5, with mold cavities 11 in which the reentrant ends 6 of the spring 4 are held.

The pads 5 are cast on at the correct angle by means of the permanent mold or casting jig shown in Figs. 5, 6 and 7, wherein it will be observed that the mold cavity 11 is inclined from the vertical at an angle equal to the angle of the slabs 1 and 2. As illustrated in Figs. 5 and 6, this permanent mold comprises a drag 15 and cope 16 with a gate 17 for each mold cavity and is illustrated with a casting therein and sectioned.

Since all the corners are made in the same permanent mold, the inner face of every pad has the same angle (as 5°) and thus when the corner fastenings are bolted or riveted onto the pads, the pad faces necessarily set them and keep them at the intended angle (say 5°) to the vertical.

When the jacket is placed on a sand mold of precisely the jacket dimensions and not forced down thereon, it acts as a rigid jacket because the corner springs are stiff enough not to deflect readily.

If the mold is of such a character that the outward pressure of the molten metal is expected to be greater than the force necessary to bend the undistorted springs, the jacket can be forced further down on the mold, spreading the sides and putting additional tension on the springs, thus adding to the compressive effect of the jacket on the mold.

The jacket is normally intended to be used on molds of the same inclination as its own sides, but can be placed on molds having faces of other inclinations and conform thereto if the sand of the molds is sufficiently hard and dense not to be injured by the torsional effect.

Inasmuch as the flask is entirely open at the corners the vexing problems of making the jacket corners fit accurately upon the corners of the

mold is entirely avoided, but the unsupported span of sand at the corners is not great enough to allow the metal to break out.

Adjustable jackets with loose hinges at the corners have sometimes been used, but the difficulty with these is that their sides are not firmly held to any basic angles or dimensions, and furthermore, when the limits of play allowed by the looseness are reached, binding occurs. This is avoided in my invention because the ends of the slabs are not at any time in contact, nor are there any attachments to the ends which come into contact. The slabs of my jacket are always held apart by the spring 4 so that there can never be any binding of rigid parts, or any concentration of load at a pinching point. Thus danger of breakage is minimized and there can be no binding.

Each side, with its fastening pads, forms a rigid element, just as though the pads and the slabs were integral. The interior faces of the pads are of substantial area so that they firmly position the slabs in the assembly at the correct angle, while the stiffness of the springs assures accurate dimensions from end to end and side to side of the jacket. The effect is of four slabs held entirely out of contact but in a definite spaced relationship both as to dimensions and angles, and each connected to the next only by a single and simple spring of sufficient rigidity to maintain the relations of the sides in ordinary handling.

Other modes of applying the principle of my invention may be employed instead of the one explained, change being made as regards the structure herein disclosed, provided the means stated by any of the following claims or the equivalent of such stated means be employed.

I therefore particularly point out and distinctly claim as my invention:

1. A foundry jacket comprising a plurality of walls arranged in a polygonal structure having open corners, and spring connections between adjacent wall ends bridging each corner, said connections including a pad formed on each end of each spring, said pad having a face secured to its respective wall end normally to fix the angular relation between the wall to which secured and the adjacent wall.

2. A foundry jacket comprising a plurality of slabs arranged to form a polygonal structure, the end of each slab being spaced from the adjacent end of the next slab, a spring at each corner bridging such space and pads molded on each end of such spring with the inner faces of said pads in fixed angular relation to each other when the spring is not stressed, said springs being separate at each corner, said pads being secured with their inner faces against the backs of said slabs, whereby said angular relation of said pad faces fixes said slabs in a corresponding normal angular relation. 5 10

3. A foundry jacket comprising a plurality of walls arranged to form a polygonal structure 15 having open corners, and spring connections between adjacent wall ends bridging each corner, said connections comprising a spring having ends defining a plane and a pad cast on each of said ends, said pad having an inner face secured to 20 the back of its respective wall normally to fix the horizontal and vertical angular relation between the wall to which it is connected and the adjacent wall.

4. A foundry jacket comprising a plurality of 25 walls arranged to form a polygonal structure having open corners, and spring connections between adjacent wall ends bridging each corner, said connections comprising a flat spring and a pad cast on each end thereof, said pad having an 30 inner face secured to the back of its respective wall normally to fix the horizontal and vertical angular relation between the wall to which it is connected and the adjacent wall.

5. A foundry jacket comprising a plurality of 35 walls arranged to form a polygonal structure having open corners, and spring connections between adjacent wall ends bridging each corner, said connections comprising a spring having ends directed reversely to and inwardly of the main 40 portions thereof, and a pad cast upon each said end, said pad having an inner face secured to the back of its respective wall normally to fix the horizontal and vertical angular relation between the wall to which it is connected and the adjacent wall. 45
